PROTECTIVE DEVICE

Leo W. Coan, Superior, Colo.

Application March 3, 1934, Serial No. 713,929

10 Claims. (Cl. 173—28)

This invention relates to improvements in devices for shielding exposed current carrying bodies such as power lines or the like, and pertains particularly to such a shield device which may be readily shifted to permit engagement with such line.

In coal mines, metal mines, quarries, factories and many other locations, power carrying lines are suspended with uninsulated areas or sections provided to permit the ready connection with the line of a current take-off device for the transmission of current to a movable electrically operated machine. As a result of this practice, frequent and serious accidents occur to those who must work in the vicinity of these lines, and the present invention has for its primary object to provide a device which may be applied to such a line to cover the uninsulated portion thereof in such a way that workmen will be protected against contact with the line, but the engagement of a current take-off hook or other device with the charged portion of the line may be easily and quickly effected.

Another object of the invention is to provide a shield or protective device of the above described character which may be readily applied to a current carrying line without having to cut the same and without the use of tools.

A further object of the invention is to provide a protective device for the above described purpose which will automatically assume a shielding position with respect to the uninsulated portion of the line to which it is attached after a take-off device has been connected with the line or disconnected therefrom.

A still further object of the invention is to provide a device of the above described character which is so designed that a take-off device of the conventional hook type may be readily coupled with the uninsulated portion of the current carrying line without requiring the operator to touch the line or protective device with his hands.

The invention will be best understood from a consideration of the following detailed description taken in connection with the accompanying drawing forming part of this specification, with the understanding, however, that the invention is not confined to any strict conformity with the showing of the drawing but may be changed or modified so long as such changes or modifications mark no material departure from the salient features of the invention as expressed in the appended claims.

55 In the drawing:—

Figure 1 illustrates the device embodying the present invention in longitudinal section, the same being shown applied to a current carrying line from which a portion of the insulation has been removed.

Figure 2 is a bottom plan view of the device illustrated in Figure 1.

Figure 3 is a longitudinal sectional view of the device like that shown in Figure 1, but showing the shiftable portion of the device in the position to which it is moved in following one method of coupling a current take-off hook with the line.

Figure 4 is a view in rear end elevation of the device.

Figure 5 is a transverse sectional view taken 15 on the line 5—5 of Figure 1.

Figure 6 is a view in front end elevation of the device.

Referring to the drawing wherein like numerals of reference designate corresponding parts 20 throughout the several views, the numeral 1 indicates the fixed portion of the protective device, while the numeral 2 indicates the shiftable part thereof. The fixed portion 1 of the device is divided horizontally to form the two blocks 3 25 and 4, the confronting faces of which have co-acting channels 5 which receive the insulated portion of the current carrying line 6 to which the device is applied. These two block portions 3 and 4 of the body are held together by the bolts 30 7 on which are threaded the wing nuts 8. It will thus be readily apparent that the device may be easily and quickly applied to the line at any point without the use of any tools as the fingers can be employed to sufficiently tighten 35 the wing nuts on the bolts to draw the two portions of the body 1 firmly together.

The shiftable portion 2 of the device is relatively long, as illustrated, and has a relatively deep channel 9 formed throughout the length 40 thereof and extending inwardly from the bottom side or face. At the free end of the body 2, the inner wall of the channel 9 is rounded, as indicated at 10, and in addition, the side walls are beveled off or inclined, as indicated at 11, to 45 facilitate the ready placement of a current take-off hook in the channel about the line 6.

Intermediate its ends, the channel 9 has the side walls and the inner or top wall cut out, as indicated by the numerals 12 and 13, so that 50 the width and depth of the channel intermediate its ends is materially increased.

The end of the body 2 opposite the rounded inner wall 10, is joined to one of the two blocks 55 of the body 1 by means of a spring actuated

hinge 14, which normally urges the body 2 to swing into a position of alinement with the body 1, as is illustrated in Figure 1.

In addition to forming the free open end of the channel with the inclined side walls 11 and the rounded inner wall portion 10 for facilitating the application of a current take-off hook to a desired portion of the wire, the longitudinal edges of the walls bordering the channel 9 are each provided with a notch 15 between the bevelled edge and the cut out areas 12.

In the use of the present device, the body 1 is clamped in the manner illustrated in Figure 1, to an insulated wire 6 in such a position that the enlarged area of the channel 9 overlies the uninsulated or stripped portion or area 16 of the line. A pole 17 having a metallic hook 18 on its end is ordinarily used for connecting a piece of electrical apparatus with a current carrying line, the hook being engaged over and in contact with the metal part of the line and the current being passed therefrom down to the pole to the desired piece of machinery. When an insulated line having an uninsulated portion is equipped with a protective device of the character herein set forth, and it is desired to couple the hook 18 of such a take-off pole with the line to remove current therefrom, two methods may be employed for effecting this connection, one of which is to engage the hook over the line, as indicated in dotted outline in Figure 1, then sliding the hook along until it abuts the rounded wall surface 10 of the channel so as to effect the swinging up of the free end of the body 2 so that continued sliding of the hook on the line will bring it to the uninsulated area 16 in the enlarged area of the channel. When this enlarged area of the channel is reached, the body portion 2 of the device will drop back to position or will be forced back by the spring of the hinge 14 and the connection between the hook and the wire will be shielded and at the same time, the hook will not be in contact with the walls of the channel of the portion 2. Another method of lifting the portion 2 of the device is to place the rounded outer portion of the hook in one of the notches 15, then force the free end of the portion upward and by quickly turning the hook, bring the free end or bill portion over the wire so that when the hook is dropped back, it will come into position over the wire and may be slipped in onto the uninsulated area 16 thereof.

From the foregoing, it will be readily apparent that a current carrying line having the uninsulated area shielded by devices of the character herein described, will be effectively prevented from causing injury to workmen who might otherwise come accidentally into contact with the live uninsulated portion thereof.

The device herein described may be formed of any suitable material which will not conduct electricity, such, for example, as wood, hard rubber, porcelain, or any other insulation material.

What is claimed is:—

1. A protective device, comprising a two-part body adapted to have an insulated current carrying line secured between the parts thereof, an elongated member pivotally attached at one end to said body and having a longitudinal channel formed therein for the reception of the current carrier, the said channel being designed to house an uninsulated portion of the carrier, and means facilitating the application of a take-off device to the uninsulated portion of the carrier, comprising a cam-like surface forming a part of a wall

of the channel at the end remote from the two part body.

2. A protective device, comprising a two-part body adapted to have an insulated current carrying line secured between the parts thereof, an elongated member pivotally attached at one end to said body and having a longitudinal channel formed therein for the reception of the current carrier, the said channel being designed to house an uninsulated portion of the carrier, and means facilitating the application of a take-off device to the uninsulated portion of the carrier, comprising a cam-like surface forming a part of a wall of the channel at the end remote from the two part body, said channel intermediate its ends being of increased width and depth whereby a take-off device engaging the uninsulated portion of the current carrier will be free from contact with the channel walls.

3. A protective device, comprising a two-part body adapted to have an insulated current carrying line secured between the parts thereof, an elongated member pivotally attached at one end to said body and having a longitudinal channel formed therein for the reception of the current carrier, the said channel being designed to house an uninsulated portion of the carrier, and means facilitating the application of a take-off device to the uninsulated portion of the carrier, comprising a notch formed in a longitudinal edge of the wall of the channel in which a take-off device may be engaged to facilitate raising the channeled body for the coupling of the device with the uninsulated portion of the current carrier.

4. Means for shielding an uninsulated portion of a current conducting line, comprising a two part body, means for securing one of said parts to the line adjacent the uninsulated portion thereof whereby the other part of the body will overlie said portion and shield the same, and means normally urging said other portion of the body into such shielding position.

5. In a device of the character described, an elongated body adapted to lie in longitudinal relation with an insulated current conductor over a bared or uninsulated portion thereof, means hingedly securing the body at one end to the insulated portion of the conductor whereby the body and attaching means is wholly supported by the conductor, and resilient means normally urging the body toward the conductor, the said body being shiftable away from the bared portion to facilitate application of a take-off conductor therewith.

6. A device adapted to be mounted as a unit upon an insulated current conductor from which a portion of the insulation has been removed and wholly supported by the conductor, comprising one member adapted to be secured to the insulated portion of the conductor, a shield hingedly secured to said member and extending therefrom longitudinally of the conductor over the portion from which the insulation is removed, and resilient means constantly urging the shield toward the conductor.

7. A protective device, comprising a two-part body adapted to have an insulated current carrying line secured between the parts thereof, an elongated member pivotally attached at one end to said body and having a longitudinal channel formed therein for the reception of the current carrier, the said channel being designed to house an uninsulated portion of the carrier, and resilient means carried by the body and normally

urging the member toward the current carrying line to maintain the uninsulated portion of the current carrier in said channel.

8. A device of the character described, comprising a body adapted to be mounted on, and secured to, an insulated current conductor adjacent to an uninsulated portion of the conductor, a shielding body joined to the first body for movement relative thereto and adapted to cover the uninsulated part of the current conductor, and means normally urging the shiftable body toward the uninsulated portion of the current conductor to shield such portion.

9. A device of the character described, comprising a body adapted to be mounted on, and secured to, an insulated current conductor adjacent to an uninsulated portion of the conductor, a shielding body joined to the first body for movement relative thereto and adapted to cover the uninsulated part of the current conductor, means

normally urging the shiftable body into operative position relative to the uninsulated portion of the current conductor to shield such portion, and means whereby the shifting of the shiftable body may be readily effected by a current take-off device for the attachment of the latter with the uninsulated portion of the current conductor.

10. A protective device of the character described, comprising a body designed to be mounted on, and secured to, an insulated current conductor adjacent an uninsulated portion thereof, a shield element hingedly attached to the body and adapted to encase the uninsulated portion of the conductor, said shield when swung in one direction uncovering the said portion of the conductor, and means facilitating the shifting of the shield relative to the conductor to permit a current take-off element to be coupled with the uninsulated part of the conductor.
